Nº 3225

WILLIAM I. PEAKE, OF NEW YORK, N. Y.

Design No. 3,225, dated November 3, 1868.

DESIGN FOR A TRADE-MARK

The Schedule referred to in these Letters Patent and making part of the same.

To all whom it may concern:

Be it known that I, WILLIAM I. PEAKE, of the city and State of New York, have originated a new Design for a Trade-Mark, of which the following is a full, clear, and exact description, reference being had to the accompanying drawing, making a part of this specification, in which—

Claim.

What I claim as my invention or production, and desire to secure by Letters Patent, is—

The design for a trade-mark, as herein set forth and shown.

Witnesses:

J. B. NONES,
SHELDON C. RAYMOND.
